TALKING MACHINE LIGHT SWITCH

Filed Jan. 22, 1921

UNITED STATES PATENT OFFICE.

OSCAR LARSEN, OF BROOKLYN, NEW YORK.

TALKING-MACHINE LIGHT SWITCH.

Application filed January 22, 1921. Serial No. 439,164.

To all whom it may concern:

Be it known that I, OSCAR LARSEN, a citizen of the United States, residing at Brooklyn, in the county of Kings and State 5 of New York, have invented certain new and useful Improvements in Talking-Machine Light Switches, of which the following is a specification.

This invention has relation to sound 10 producing machines, with particular reference to the cabinet type having a hinged lid, and has for an object to provide a means of illumination to be located adjacent the turn table, with means for energizing the 15 source of illumination automatically upon the elevation of the lid, and to discontinue energization when the lid is closed.

Another object of the invention is to provide an attachment for cabinet talking 20 machines having hinged lid, said attachment to be located within the cabinet and having means constituting a brace for the lid to retain the same in an elevated position, said means acting as a circuit closer to complete 25 a circuit through a source of illumination and a source of current to illuminate the turn table and the upper part of a talking machine.

In addition to the foregoing this invention 30 comprehends improvements in the details of construction and arrangement of parts to be hereinafter described and particularly set forth in the appended claims.

In the accompanying drawings in which 35 similar and corresponding parts are designated by the same characters of reference throughout the several views in which they appear.

Figure 1 is a fragmentary view in side elevation of the upper portion of a cabinet talking machine illustrated in dotted lines the embodiment 40 therein of my invention.

Figure 2 is a detail view on an enlarged scale illustrating the mechanism; and

Figure 3 is a vertical section taken on the 45 line 3—3 of Figure 2.

With reference to the drawings, 10 indicates the cabinet of a talking machine and 11 a lid hinged at 12 in the usual manner 50 and having a brace bar 13 which is pivoted to the lid as at 14. The lower end of the brace bar 13 extends into a device shown in detail in Figures 2 and 3 and consisting of a pair of spaced plates 15 and 16, having a 55 guide member 17 interposed therebetween, said guide member having a substantially

triangular slot one side of which is curved as indicated at 18 and the other straight as indicated at 19, and an inclined upper connecting portion or groove 20, the upper wall 60 of said groove 20 having an obstruction 21 located therein substantially intermediate the ends of said groove. The lower wall of the groove 20 is provided with a recess 22 in which is mounted part of a circuit closing 65 mechanism consisting of the base member 23 of insulating material having a pair of spring fingers 24 and 25 mounted thereon, each of said spring fingers having a projection 26 formed therein, said projections 70 being located opposite each other and directed toward each other with the terminals of the spring members 24 and 25 beyond said projections extending in diverging relation and substantially in alignment with 75 the wall of the slot 20 so as to provide configurations thereof. A lateral projection 27 is mounted upon the lower end of the brace bar 13 said projection 27 having a pair of recesses 28 in its side adapted to receive the 80 projection 26 of the spring fingers. Mounted upon the lower end of said member 27 is a strip of insulating material 29 for a purpose to be presently noted. I provide upon 85 the upper surface of the talking machine adjacent the turn table an incandescent bulb 30, one terminal of which is connected by means of the lead 31 to the spring finger 25, and the other terminal of the bulb connected by means of the lead 32 to the spring finger 90 24. Interposed in said lead 32 is a source of current 33.

When the lid 11 is in a lowered position as shown in dotted lines in Figure 1 it will be observed that the brace bar 13 hangs substantially vertically and the projection 27 will be in the lower end of the triangular groove or substantially at the junction of the grooves 18 and 19, said projection however lying more in the groove 19 than in 95 the groove 18. As a result of this position when the lid 11 is elevated the projection 27 will ride upwardly within the groove 19 and will then be directed into the groove 20, impending upon the projection 21 which will 100 cause the brace bar 13 to be directed downward slightly and when in this position by lowering the lid 11 the projection 27 may be inserted between the spring fingers 24 and 25, thus completing the circuit through 105 the leads 31 and 32, the bulb 30 and the source of current 33. The incandescent 110

lamp will then be illuminated and permit the record interchanged. By elevating the lid 11 the projection 27 will be disengaged from the spring fingers 24 and 25 and striking the obstruction 21 will be directed into the channel 20 again and will ride along the same until the projection arrives above the upper end of the groove 18. By lowering the lid the brace bar will be disposed again 10 in its initial position as shown in dotted lines in Figure 1. The circuit will thus be broken. It will be observed that owing to the configuration of the projection 27 and the spring fingers 24 and 25 in conjunction 15 with the strip of insulating material 29 the circuit will be quickly broken when the projection 27 is withdrawn from between the spring fingers, thus preventing the formation of an arc.

20 Thus it will be seen that I have provided a novel device which may be embodied in talking machines of practically any type, the upper end of the plate 15 having a flat plate portion 34 formed therein which is 25 adapted to be secured to the top wall of the talking machine by means of screws and is provided with a slot through which the brace bar 13 operates. Owing to this arrangement a source of illumination is provided automatically at times when the same is required without extra attention. Furthermore the embodiment of the apparatus in the talking machine does not detract from the appearance thereof in any 30 manner. Other useful advantages will readily occur to those familiar with the art to which this invention appertains.

While I have illustrated and described my invention with some degree of particularity 40 I realize that in practice various alterations therein may be made. I therefore reserve the right and privilege of changing the form of the details of construction or otherwise altering the arrangement of the correlated parts without departing from the spirit of the invention or the scope of the appended 45 claims.

Having thus described my invention what I claim as new and desire to secure by 50 United States Letters Patent is:—

1. An attachment for talking machines comprising a plate having a substantially horizontal groove therein, the lower wall of the groove being recessed, a support of insulated material received in the lower portion of said recess, a pair of spring contact fingers mounted on said support and having their terminals extended into the upper por-

tion of the recess to form a continuation of the walls of the recess, a brace member for attachment to the lid of the talking machine, and a projection carried by said brace member and adapted to ride on the lower wall 60 of the groove and the contact fingers in making and breaking the circuit.

2. In combination with a cabinet talking machine including a lid, a brace member pivoted to said lid, a substantially vertical 65 guide member having a continuous substantially triangular groove embodying an upper inclined arm which has its lower wall provided with a recess, the upper wall of said upper inclined arm being provided 70 with a projection arranged above said recess, a projection extending from the brace member and adapted to travel in said triangular groove, and a pair of spaced contact members arranged in said recess to be bridged 75 by the projection of said brace in one position.

3. An attachment for talking machines comprising a pair of spaced plates arranged in a vertical position in a talking machine 80 cabinet, a guide plate arranged against one of said first named plates and spaced from the other, said guide plate being provided with a substantially triangular continuous slot, one wall of the slot being provided with 85 a recess, a pair of spaced contact members arranged in said recess, a brace member pivotally connected to a lid of a talking machine and adapted for engagement between the guide plate and one of the first mentioned plates, and a projection on the brace member adapted for travel in said slot of the guide plate and for engagement with the spaced contact members.

4. An attachment for talking machines 90 comprising a plate having a lateral triangular groove and the inner wall of the groove recessed a support of insulated material in said recess, a pair of spring fingers mounted on said insulating material and 100 having their terminals bent to form a continuation of the recessed wall, a brace member for attachment to the lid, and a metallic projection extending laterally of the brace member adapted to ride in the groove and to 105 engage between the contact fingers to create electrical connection therebetween.

In testimony whereof I affix my signature in presence of two witnesses.

OSCAR LARSEN. [L.S.]
